(57) **CLAIM**

The ornamental design for a portion of a watch, as shown and described.

DESCRIPTION

FIG. 1 is a perspective view of a portion of a watch showing my new design;

FIG. 2 is a front view thereof;

FIG. 3 is a top view thereof;

FIG. 4 is a bottom view thereof;

FIG. 5 is a right side view thereof,

FIG. 6 is a left side view thereof; and,

FIG. 7 is a bottom view thereof.

The broken line showing of various regions of the watch is for illustrative purposes only and forms no part of the claimed design.
